UNITED STATES PATENT OFFICE

2,574,424

RATCHET SPANNER WRENCH

Casimere A. Szetela, Adams, Mass., assignor to
General Electric Company, a corporation of
New York

Application August 23, 1949, Serial No. 111,908

2 Claims. (Cl. 81—90)

1

My invention relates to hand tools, and more particularly to spanner wrenches.

In various types of shop work, and in many manufacturing operations, it frequently becomes necessary to apply a turning force to a body having a large diameter, and under conditions where the space available for applying the necessary turning force is restricted.

It is an object of this invention to provide a wrench capable of turning bodies of large diameter, and having a turning handle which has an adjustable position with respect to the object which is being turned.

It is a further object of this invention to provide a wrench for turning bodies of large diameter which will be easy to operate where working space is restricted.

In accomplishment of these objectives, this invention provides a ratchet spanner wrench having an arcuate gripping spanner element and a handle element which are relatively movable by means of slide elements pivotally mounted on the handle which move along grooved tracks on the arcuate spanner element.

The features of this invention which I believe to be novel are set forth with particularity in the appended claims. My invention itself, however, both as to its organization and use, together with further objects and advantages thereof, may best be understood by reference to the following description taken in connection with the accompanying drawing in which Fig. 1 represents a plan view of the wrench of my invention; Fig. 2 represents a cross-sectional view along line 2—2 of the same wrench; and Fig. 3 represents a view, partially cut away, of a modified form of wrench in accordance with my invention.

Referring now to the drawing, there is shown in Fig. 1 a disk 1 which it is desired to turn, having symmetrically-spaced recesses 2 cut into its outer periphery. These recesses may be in the form of notches or drilled holes. The wrench 3 of my invention is comprised of an arcuate spanner element 4 and a handle 5. Integrally connected to the spanner element 4 is a projecting ear 6 which is adapted to fit into the recesses 2 on the outer periphery of the disk 1. The projecting ear 6 is either rectangular or round in shape, depending upon the configuration of the recesses 2 on disk 1 with which it is designed to mate.

In accordance with my invention, the spanner element 4 is provided with recessed tracks 7 and 8 of arcuate shape which extend on both sides of the spanner element for the greater part of its length. The object of arcuate recesses 7 and

2

8 is to provide tracks for slide elements 9 and 10, which, as will be explained hereafter, are adapted to slide along the recesses 7 and 8 to position the handle 5 preparatory to turning the disk 1. Slide elements 9 and 10 are pivotally connected to handle extensions 11 and 12, respectively, by means of pins 13 and 14. The handle extensions 11 and 12 are rigidly attached on each side of the main body of the handle 5 by any suitable method, such as welding.

A pawl 15 is pivotally mounted with respect to the handle 5 by means of a screw 16 having its head fitting into a recess in handle extension 11, its threaded end screwed into handle extension 12, and its middle portion having a smooth surface about which the pawl 15 pivots.

The spanner element 4 is provided with ratchet teeth 17 on its outer arcuate surface, which are adapted to engage pawl 15. The pawl 15 is maintained in engagement with the ratchet teeth 17 by means of a spring 18 which bears against the pawl, with the other end of the spring 18 being rigidly fastened to the handle member 5.

In the normal operation of the spanner wrench 25 of my invention, the inner arcuate surface of the spanner element 4 of the wrench is applied to the outer periphery of the disk which is to be turned, in such manner that the projecting ear 6 of the spanner element 4 fits into one of 30 the recesses 2 in the disk 1. The handle 5 of the wrench may then be adjusted to any desired position with respect to the spanner element 4 by moving the handle and its attached slide elements 9 and 10 along the grooved tracks 7 and 8. 35 When the movement of the handle is in a counterclockwise direction, with respect to the view shown in Fig. 1, the pawl 15 will slide over the ratchet teeth 17 of the spanner element 4. If the movement of the handle is in a clockwise 40 direction, the pawl 15 may be manually retracted from the ratchet teeth 17 during the period of the movement.

After the slide elements 9 and 10 have been moved to the desired position along the grooved 45 tracks 7 and 8, the handle 5 may then be pivoted about pins 13 and 14 until the handle assumes the angle which the operator desires. The pawl 15 is held in engagement with ratchet teeth 17 by means of spring 18, and serves as the means 50 whereby force applied to handle 5 is communicated to spanner element 4 and thence to disk 1.

After the handle is adjusted to the desired 55 position, if a clockwise turning force is then exerted on the handle 5, the entire wrench assembly, including the spanner element 4, the handle 5, the slide elements 9 and 10, and the pawl 15, turn as a unit. At the same time, the disk

1 is rotated. The turning force exerted on the handle 5 is communicated to the spanner element 4 and disk 1 by the engagement between the pawl 15 and ratchet teeth 17.

It will be seen that my spanner wrench has great adjustability with regard to the position which the actuating handle 5 may occupy with respect to the arcuate-shaped spanner element 4. Due to the provision of the slide elements 9 and 10, the pivot point of handle 5 may be moved to any position along the tracks 7 and 8, at which point the handle may be pivoted about the slide elements to any convenient angle, provided the angle of the handle 5 with respect to spanner element 4 is not more than approximately 60 degrees. When the axis of the handle 5 is positioned at angles of more than 60 degrees with respect to the spanner element 4, the horizontal component of force exerted on the slider elements 9 and 10 will be such as to cause a relative motion between the slide elements 9 and 10 and the spanner element 4. When a turning force is being exerted on the handle 5, there should be no relative motion between the slider members 9 and 10 and spanner element 4. As mentioned hereinbefore, the only time when there should be relative motion between these members is when the handle 5 is being adjusted into position with respect to the spanner element 4. It is obvious that this adjustability of the position of the handle 5 is of considerable advantage, since it permits easy operation of the wrench under many confined and space-restricted conditions where operation of spanner wrenches heretofore known would be very difficult.

A further feature of my construction is the fact that an eccentric screw 16 is provided to hold the pawl 15 in position with respect to the handle 5, thereby permitting adjustment of the pawl 15 when grooved tracks 7 and 8 become worn and cause a change in the position of the pawl 15 with respect to the ratchet teeth 17. This condition can be corrected by turning the screw 16 so as to raise the axis about which the pawl 15 pivots.

A modification of my invention is shown in Fig. 3. This modified construction is provided for an application in which the conditions under which the wrench will be used make it necessary that the handle 5 of the wrench be advanced to positions where the axis of the handle 5 is at an angle of more than 60 degrees with respect to the spanner element 4. As mentioned hereinbefore, when the handle 5 is advanced to a position of more than approximately 60 degrees with respect to the spanner element 4, the horizontal component of the force exerted upon the handle will be such as to cause slide elements 9 and 10 of the type shown in Figs. 1 and 2 to slide along the tracks 7 and 8 when a turning force is being exerted on handle 5, instead of remaining stationary as they should.

In the modified structure of Fig. 3, the motion of slide elements 9 and 10 is prevented by providing one edge of the tracks 7 and 8 with ratchet teeth 19 with which the slide elements 9 and 10 can engage. In this modified structure, the slide elements 9 and 10 are made narrower than the form of slide elements shown in Figs. 1 and 2, and do not fill the full width of the track recess as do the slide elements 9 and 10 of Figs. 1 and 2. This permits the slide elements shown in Fig. 3 to pivot into engagement with the ratchet teeth 19 on the edge of the grooved track. By

means of this arrangement, the handle 5 may be advanced to a position beyond the limiting angle of 60 degrees with respect to the spanner element 4 which must be observed when using the form of my invention shown in Figs. 1 and 2.

While there have been shown and described particular embodiments of my invention, it will be obvious to those skilled in the art that various changes and modifications can be made therein without departing from the invention and, therefore, it is aimed in the appended claims to cover all such changes and modifications as fall within the true spirit and scope of the invention.

What I claim as new and desire to secure by Letters Patent of the United States is:

1. An arcuate spanner wrench of the type having at least one projection engaging a mating recess in the object being turned, comprising an arcuate spanner element with which said projection is integral, said spanner element having a grooved track on each of its two opposite arcuate surfaces which are perpendicular to the axis of rotation, a handle for said wrench, slide elements pivotally connected to said handle at the end thereof adjacent said spanner element, said slide elements being movable in said grooved tracks to permit adjustment of the position of said handle relative to said spanner element, ratchet teeth on the radially outer arcuate surface of said spanner element, and a pawl pivotally mounted on said handle and engageable with said ratchet teeth to communicate turning force applied to said handle to said spanner element, thereby applying a turning force to said object being turned.

2. An arcuate spanner wrench of the type having at least one projection which engages a recess in the object being turned, comprising an arcuate spanner element with which said projection is integral, said spanner element having a grooved track on each of its two opposite arcuate surfaces which are perpendicular to the axis of rotation, a handle for said wrench, slide elements pivotally connected to said handle at the end thereof adjacent said spanner element, said slide elements being movable in said grooved tracks to permit adjustment of the position of said handle relative to said spanner element, at least one edge of each of said grooved tracks having teeth to permit locking said slide elements against motion, ratchet teeth on the radially outer arcuate surface of said spanner element, and a pawl pivotally mounted on said handle and engageable with said ratchet teeth, so that turning force applied to said handle is communicated through the engagement of said pawl and ratchet teeth to said spanner element and thence to the object being turned.
